UNITED STATES PATENT OFFICE

KONRAD JAGSCHITZ, OF MAINZ, GERMANY, AND PAUL M. KUEHN, OF BALTIMORE, MARYLAND, ASSIGNORS OF ONE-HALF TO MASCHINENFABRIK AUGSBURG-NURNBERG, A. G., OF NUEREMBERG, GERMANY, A CORPORATION OF GERMANY, AND ONE-HALF TO THE BARTLETT HAYWARD COMPANY, OF BALTIMORE, MARYLAND, A CORPORATION OF MARYLAND

GASOMETER

Application filed March 10, 1927. Serial No. 174,347.

This invention pertains to gasometers, of the socalled waterless type, and has to deal more particularly with the means employed for withdrawing the used sealing liquid from the lower portion of the holder, separating the water therefrom, and thereafter securing proper distribution of the sealing liquid to the upper portion of the holder.

Holders of the type to which this invention is applicable are shown, for instance, in United States Letters Patent Nos. 1,275,698 and 1,481,099. So, also, in United States Letters Patent No. 1,545,960 there is shown collecting means for the sealing liquid employed in holders of the type claimed in said earlier patents and as set forth herein.

The present apparatus is in a sense an improvement upon the apparatus set forth, in the last numbered patent. Generally speaking, it may be said to comprise a series of units located about the base of the holder, each unit receiving, from a trough or channel located within the holder at its base, the liquid sealing medium, as tar, which flows down the inner face of the wall of the holder, the lighter oils, as well as such water as may be present in the tar and that which condenses upon the wall of the holder. Each of said units is provided with means for separating the tar from the water, means for returning the tar to the upper portion of the holder for use in connection with the sealing elements of the movable closure or piston; and means for forcing the water (and light oils) to a settling tank common to all the units where a separation of any tar carried by the water is effected, the tank also serving as a reservoir for tar for the holder.

The tar pump in each unit is electrically driven and the circuit therefor is controlled through a float actuated switch. The water or skimmer pumps of the various units are electrically interconnected and means is preferably provided to cause them to be operated periodically so that in effect the apparatus as a whole is self controlling requiring but a minimum of attention and inspection.

An embodiment of the invention is shown in the annexed drawings, wherein:

Figure 1 is an elevation, partly in section, and more or less diagrammatic, of a gas holder with the system above outlined associated therewith,

Figure 2 a transverse horizontal section on the line II—II of Figure 1,

Figure 3 a horizontal sectional view taken on the line III—III of Figure 4, showing one of the skimmer tanks or units, with its tar return pump and its water or skimmer pump; and the settling and supply tank which is in communication with the water lines leading from the various skimmer pumps, the settling tank being shown on a somewhat smaller scale,

Figure 4 a vertical sectional view of one of the skimmer tanks and the settling supply tank taken on the line IV—IV of Figure 3,

Figure 5 a vertical sectional view of the skimmer tank and a portion of the holder, taken on the line V—V of Figure 3,

Figure 6 is a similar view on the line VI—VI of Figure 3,

Figure 7 a like view on the line VII—VII of Figure 3,

Figure 8 a vertical sectional view of the settling supply tank taken on the line VIII—VIII of Figure 3,

Figure 9 a like view of the skimmer tank on the line IX—IX of Figure 3,

Figure 10 a view, more or less diagrammatic, of the timing mechanism and circuits for the skimmer pumps, and

Figure 11 a detail view of a portion of the timing mechanism, the same being shown in plan with parts broken away.

In the drawings 1 denotes the gas holder shell or body and 2, Figures 1, 2 and 5, the piston or movable closure which, as in the patents above, is surrounded by an annular trough 3 designed to hold a body of tar. The tar acting in conjunction with rubbing bars or shoes 4 which are held outwardly in contact with the adjacent face of the holder shell, effects a gas-tight joint around the piston, the tar gradually passing downwardly between the rubbing bars and shell and flowing into an annular trough 5 located at the base of the shell. It is to be understood, however, that the invention is

not limited to the specific form of rubbing bar as herein shown.

As above noted, with the present invention it is proposed to employ a series of skimming tanks located about the base of the holder, the number of course depending upon the size and diameter of the holder. In the instant case, see Figure 2, eight of such tanks are shown equi-distantly spaced about the tank and, inasmuch as said tanks and the associated parts are the same, a description of one will suffice for all.

The tanks indicated as a whole by 6 are located adjacent the base of the holder, being spaced therefrom by a housing or chamber indicated generally by 7 in which are located the skimmer and tar pumps herein-after specifically referred to.

The tank is divided into three compartments or chambers designated respectively by 8, 9 and 10. Chamber 8 hereinafter designated the skimmer or water skimmer pocket is formed by a vertical partition 11, extending from the inner wall 12 of the tank to the outer wall 13 of the tank. Wall or partition 11 stops short of the top 14 of the tank and likewise terminates short of the bottom 15 of the tank and said pocket 8 is closed by a bottom 16.

Chambers 9 and 10 are formed within the tank by a vertically disposed partition 17 extending from the inner to the outer walls 12 and 13 thereof, said partition making a gas-tight fit with the top 14 but terminating short of the bottom 15, Figures 5 and 9, so that tar may flow from chamber 9 beneath said partition to the tar chamber 10.

At each of the skimmer tanks means is provided for withdrawing the water and tar from the gutter 5 and disposing of the same in such manner that the tar will be segregated from the water and light oils—the tar being returned to the upper trough 3 while the water and light oils are forced to the settling tank and ultimately to the gas company's separator. The water handling means will be first described.

Referring more particularly to Figures 3, 4, 7 and 9, it will be noted that there is provided a casting 18, Figures 8 and 7, which opens through the wall of the holder directly into the gutter 5, said casting carrying an adjustable weir 19, the upper edge of which is normally set above the normal tar level of the gutter. The casting, at its lower end, is connected to a pipe 20 which in turn is connected to the intake fitting 21 of an electrically driven pump 22. Said fitting is also connected to a pipe 23, the inner end whereof extends into and downwardly in the pocket 8, see Figure 7.

Valves 24 and 25 are located in the pipes 20 and 23, respectively, so that the pump, when in operation may draw water through the pipe 20 or the pipe 23, as the case may be.

Normally the valve 24 is open and the valve 25 closed so that the pump tends to draw water from the gutter 5 through casting 18 over the weir 19 and through the pipe 20.

The outlet pipe of the pump is designated by 26, a check valve 27, to prevent reflow of water therethrough, being located in said pipe. A valve 28 is also placed in the pipe 26 outward of the check valve 27 and the pipe, as indicated in dotted lines in Figures 2, 3 and 4, is connected into a main 29. Said main discharges into the main tar reservoir and settling tank denoted by 30, Figures 1, 2, 3, and 4 and hereinafter set forth in detail. The various pumps 22 are designed to be simultaneously and automatically operated though of course they may be thrown into operation by hand in so far as the generic invention is concerned.

As above indicated, the valve 25 is normally closed but when it is desired to withdraw the water from the pocket 8 through the pipe 23 the valve 24 will be closed and valve 25 opened at which time, if the pump is in operation, the water will be withdrawn from the pocket 8 and discharged to the main 29.

The tar flows from the gutter 5 into the chamber 9. To this end there is provided an intake 31 having the form of an elbow with the mouth opening downwardly and toward the bottom of the gutter. A pipe 32 having a valve 33 located therein extends to the chamber or compartment 9 where said pipe opens into an adjustable overflow weir 34. A pressure equalizing pipe 35 extends from the upper part of the casting 18 into the upper part of the skimmer tank or, more specifically, into the upper part of the chamber 9 so that the same gas pressure exists within said compartment as exists within the holder.

The tar flowing into the chamber 9 will, of course, pass into the compartment or chamber 10 beneath the partition 17 from which the tar is withdrawn periodically. The water and light oils which pass into the chamber 9, along with the tar, through the pipe or conduit 32 will, of course, tend to rise upon the surface of the tar and will overflow into the skimmer pocket 8 from which it is withdrawn from time to time, as above indicated, by manipulation of the valves 24 and 25. The tar thus segregated in the main from entrained water and oil passes, as above indicated, into the chamber 10 beneath the partition 17.

In order that the attendant may ascertain whether or not water is within the chamber 9 or, in other words, whether there is a layer of water on the tar, above the top of the pocket 8, there is provided a test pipe, best shown in Figures 3, 6 and 7, said pipe being denoted by 36. The test pipe is mounted for rotation in a suitable bearing 37 carried

by the wall 13, the inner end of the pipe being curved while the outer portion is provided with a handle and indicator 38 by which the pipe may be rotated. The outer end of the pipe is provided with a valve 39, which, when open, allows outflow through the pipe 36. In the use of this structure the attendant, taking hold of the handle 38 will rotate the pipe so as to throw the inner end thereof upwardly. Valve 39 then being open, water will flow through the pipe 36 and into a waste tank 40 located outward of the skimmer tank wall 13. By turning the pipe the attendant can readily gauge the depth of the water within the skimmer tank, drawing the water off through said pipe 36 or, if need be, manipulating valves 24 and 25 to withdraw the water from the water pocket 8 and thus lower the level of the water above the tar within the skimmer tank.

The separated, or what might be termed cleaned, tar which flows into the compartment 10 is drawn therefrom by an electrical- 25 driven pump denoted generally by 41, see Figures 3, 4 and 5. The intake of the pump is connected through a pipe 42 which extends downwardly toward the lower portion of the chamber 10 and the outflow side of the pump is connected by a main 43 which leads upwardly alongside of the holder to a distributing box 44 which discharges into the shell of the holder above the moveable piston or closure 2.

A check valve 45 is preferably provided in the main 43 to prevent reflow of the tar there- 35 through. The tar pump is designed to be brought automatically into operation and to this end there is provided a float 46, see Figures 3, 5 and 9, which float is interconnected with a quick throw switch, indicated generally by 47, controlling the current leading from the source of power to the motor. Inasmuch as such devices are well known it is deemed unnecessary to disclose the same in detail nor to show the circuits leading to the motor driven pump 41. It will thus be seen that when the cleaned tar rises in the chamber 10 to the requisite height, floats 46 will close the circuit and start the pump 41 into operation, thus forcing the purified tar to the distributing box 44 and into the holder above the moveable piston or closure. Thus, while the water and light oils, which are skimmed off of the tar both from the gutter 5 and from within the skimmer tank, are re- 5 turned to a settling tank, the purified tar is returned directly to the holder.

The settling tank 30, as it may be termed, acts as a reservoir for the tar and also as a further means of removing any tar which may be carried from the various skimming tanks through the main 29 to said settling tank 30. Said tank is best shown in Figures 3, 4 and 8.

Main 29 or, more strictly speaking, the two

branches thereof which lead from the various skimmer tanks to either side of the settling tank, are connected into a riser 48 which is connected at its upper end to a lateral or branch pipe 49 extending into the settling tank 30. A pipe 50 extends upwardly from the inner end of the lateral 49 and is sur- 70 mounted by an overflow or distributing member 51. Thus the water, with such light oils as may be mixed therewith, passes from all of the skimmer pumps to the tank 30 where 75 it flows outwardly from the head 51 and onto the body of the tar which is maintained with- in the tank. The water is designed to be withdrawn from the tank from time to time and to this end there is provided an off-take 80 pipe 52 provided with an intake nozzle 53 at its outer end with which is associated a pair of floats as 54. The opposite end of the pipe 52 is swiveled upon a suitable connection 55 which leads through a pipe 56 to a pump 57. 85 The outlet of the pump is connected through a main 58 leading to the gas plant, not shown.

The float will, of course, maintain the suc- 90 tion nozzle 53 slightly below the top of the water and to prevent the nozzle from swing- 95 ing downwardly too far and thus get into the zone of the tar within the tank, a stop chain 59 is connected to the pipe 52 and a fixed portion of the tank housing.

Tar will, of course, accumulate within the tank 30 and to remove the same, piping, as best shown in Figures 3, 4 and 8, is employed.

A pipe 60 extends outwardly from the holder 1 and is connected to the tank 30 through a branch 61 and interconnected vertically disposed pipes 62 and 63, pipe 63 being open at its lower end, vented at its upper end, and terminating short of the bottom of the tank 30. When the water reaches a level, as shown in Figure 8, within the tank 30 the tar will be forced upwardly in the pipe 63, will thence flow outwardly from the upper end thereof into pipe 62 through branch 61, through pipe 60 and into gasometer or, more specifically, into gutter 5.

The tar may be applied to the reservoir 30 in any desired way but in the instant case there is shown a supply pipe 64, Figures 3, 4 and 8, which is interconnected by suitable valved branches 65 and 66 with the tank 30 and with a fitting carried at the outer end of the pipe 60. The valves, of course, after the tank 30 and the gutter and skimmer tanks have been filled to the requisite degree, 115 will be closed.

As heretofore stated, it is designed to have the skimmer pumps 22 operate automatically and at timed intervals. To this end any suitable timing mechanism may be employed, 125 which timing mechanism preferably includes a manually operable circuit closer so that the pumps may be thrown into action between intervals or operation by the timing mechanism, in case of need, or may be thrown 130

into operation manually should the timing mechanism become ineffective.

In Figures 10 and 11 a timing mechanism, together with the circuits, is disclosed, more or less diagrammatically, whereby the above operations may be effected. A three phase power line is shown, Figure 10, and so indicated by the legend, and interposed in the line is a switch designated generally by 67 which controls the current leading to the motor circuits and so marked.

The coil 68, employed to actuate the switch, is energized and de-energized by a timing mechanism which automatically 15 throws the coil into and out of action and consequently opens and closes the switch and motor circuit. Said mechanism may be of any form desired but in the present case a simple embodiment is illustrated.

20 A constantly operating motor 69 drives a worm 70 which in turn is in mesh with a worm gear 71 secured upon a shaft 72. Said shaft, at its other end, carries a worm 73 meshing with a worm wheel 74 mounted 25 upon a shaft 75. The wheel 74, or more specifically the body thereof, will be formed of a suitable dielectric material such as a phenol condensation product and has secured to it a 30 sector-shaped contact shoe 76, the outer face whereof is formed of suitable conducting material. The shaft 75 carries a collar 77 having a tooth 78 projecting laterally therefrom and adapted to enter one of a series of interdental spaces formed between the teeth 35 79 produced upon the periphery of a disk or wheel 80. The member 80 is shown as provided with forty-eight teeth and the gearing is so arranged as to produce a complete revolution of the member 74 once in every thirty 40 minutes and as a consequence the member 80 will be revolved once in every twenty-four hours. Said member 80 has secured to it a series of outwardly extending pins 81 formed of suitable dielectric material such as a phenol condensation product and spaced about 45 said member 80 as desired.

Each of the pins 81 carries a metallic sleeve 82 adapted to be brought into contact, as the member 80 is rotated, with a pair of 50 brushes 83 and 84, the former of which is included in the branch 85 of the power line. A second pair of brushes 86 and 87 are so mounted as to come into contact with the conducting shoe 76 when the latter is brought 55 into contact with the same upon rotation of the member 74. Brushes 84 and 86 are interconnected as at 88 and the brush 87 is in the branch 89 of the power line.

A manually operated switch 90 may be 60 employed to close the circuit independently of the timing mechanism, a cross connection 91 extending from the line 85 to one of the switch terminals as is clearly shown in Figure 10. Normally the switch will be in the position shown so that the line 89 will not

be interrupted or, in other words, so that the timing mechanism will be in circuit.

From the description just given it will be seen that with the pins 81 carried by the member 80 the skimmer pumps will be 70 thrown into operation automatically every eight hours or, if need be, by changing the position of the pins the timing interval between successive operations may be varied to suit conditions.

75 It is thought that the operation of the apparatus as a whole will be understood from the foregoing description, but a brief résumé will be given.

It is, of course, to be assumed that the proper and requisite amount of sealing medium, as tar, has been introduced into the apparatus, that is to say that the upper trough is filled, gutter 5 filled (or partially so), chambers 9 and 10 partially or fully 80 charged, and tank 30 likewise filled say to half its capacity. If now the circuit is closed through the timing mechanism or through manipulation of the switch 90, the skimmer pumps will come into operation and draw 85 the water from off of the tar within the gutter 5, the water flowing over the weir 19 to the pump 22,—this assuming the valve 24 is open, and the water and light oils will then be forced through the mains 29 to the settling tank 30. As the tar continues to flow down the inner face of the tank into the gutter 5 it will be gradually forced upwardly through the member 31, past valve 33, through pipe 32, and over the weir 34 into 90 the chamber 9. It will then pass beneath the partition 17 into the chamber 10 free of water or lighter oils. When it rises to a given height in said chamber 10, float 46 will throw the actuating switch 47 and thus bring the tar pump 41 into operation thereby withdrawing the tar from the compartment 10, through pipe 42, upwardly into the distributing boxes 44, through the mains or 95 pipes 43.

10 When the tar has been pumped out to a given level from the chamber 10 the float will drop and the switch 47 will be opened thereby bringing the pump 41 to rest.

The water which passes through the mains 11 29 from the various skimmer tanks to the settling tank 30 will gradually build up upon the tar within the tank and its weight will necessarily depress the tar level within the tank and cause tar to flow upwardly through the pipe 63, thence downwardly through the pipe 62, into the pipe 60, and back to the gutter or trough 5.

12 The attendant may withdraw the water from the tank 30 as necessary by bringing the pump 57, Figure 4, into operation, the water thus removed passing through the line 58 back to the gas house or plant where it may be treated for recovery of any material or substance carried thereby.

It will thus be seen that the apparatus is automatic in its operation and that the water is removed from the tar in the gutter at a plurality of points spaced around the holder.

5 Removal at a plurality of points is found to be more efficient than seeking to draw the water from a single point in the trough as to seek its removal from a single point necessitates flow of the water for a distance of at least half the circumference of the tank.

What is claimed is:

1. In a gas holder the combination of a shell or body; a piston like closure therefor; sealing means carried by the closure acting

15 against the face of the body in conjunction with a liquid sealing medium; a gutter located in the lower portion of the holder in which the down-flowing liquid collects; a series of pumps located at intervals about

20 the holder, the intakes of said pumps being connected to the gutter for withdrawal of water which lies upon the sealing medium within the gutter; a settling tank adapted to contain sealing medium, and into which tank

25 the water is discharged; and means for conducting sealing liquid from the tank to the holder as such liquid is displaced by the water.

2. In a waterless gas holder the combination of a shell or body; a piston like closure therein; a collecting gutter for the liquid sealing medium employed in conjunction with the closure; a plurality of tanks arranged about the same; means for withdraw-

30 ing the sealing medium from the gutter to each of said tanks; means located within said tanks for separating water and light oils from the sealing medium; automatic means for forcing the purified sealing medium back

35 into the holder; means within the tanks for collecting the separated water and light oils; a pump located at each tank, the intake whereof is connected with the upper portion

40 of the gutter; a settling tank adapted to contain a body of sealing liquid; a main connecting the pump discharges with the settling tank; and means for conducting sealing liquid from the settling tank to the gutter as such liquid is displaced by the incoming

45 water.

3. In combination with a gas holder body or shell; a piston like closure therefor; sealing means involving the use of a liquid sealing medium between the closure and the wall

50 of the holder; means located at the base of the holder for collecting the sealing medium and any entrained liquid of lighter specific gravity; a series of tanks located about the holder; connections extending from the lower

55 portion of the collecting means to each tank for removing the sealing medium from said means to the tanks; means located in the latter for effecting a separation of water and light oils from the sealing medium; means

60 for returning the cleansed sealing medium

from the tanks to the upper portion of the holder; a settling tank, containing sealing medium, said tank being connected with the collecting means through an open but normally inoperative connection; and means 70 for withdrawing water and light oils from the upper surface of the sealing medium held in the collecting means at a plurality of points about the holder, and discharging the same into the settling tank, whereby the sealing medium will be displaced and caused to flow into the collecting means at the base of the holder. 75

4. In combination with a gas holder body or shell; a piston like closure therefor; sealing means involving the use of a liquid sealing medium between the closure and the wall of the holder; means located at the base of the holder for collecting the sealing medium and any entrained liquid of the lighter specific 80 gravity; a series of tanks located about the holder; connections extending from the lower portion of the collecting means to each tank for removing the sealing medium from said means to the tanks; means located in 85 the latter for effecting a separation of water and light oils from the sealing medium; means for returning the cleansed sealing medium from the tanks to the upper portion of the holder; a settling tank, containing 90 sealing medium, said tank being connected with the collecting means through an open but normally inoperative connection; means for withdrawing water and light oils from the upper surface of the sealing medium held 95 in the collecting means at a plurality of points about the holder, and discharging the same into the settling tank, whereby the sealing medium will be displaced and caused to flow into the collecting means at the base 100 of the holder; and means for removing the accumulated water and light oils from the settling tank. 105

5. In combination with a gas holder body or shell; a piston like closure therefor; sealing means involving the use of a liquid sealing medium between the closure and the wall of the holder; means located at the base of the holder for collecting the sealing medium and any entrained liquid of lighter specific 110 gravity; a series of tanks located about the holder and interconnected with the collecting means for withdrawing the collected material of heavy specific gravity; means located within each of the tanks for segregating any entrained water or light oils from the heavier sealing material; means for forcing said purified sealing material back to the upper portion of the holder; a settling tank containing sealing medium, said tank being 115 connected with the collecting means through an open but normally inoperative connection; and means for withdrawing the water and light oils from off the sealing medium within the collecting means and discharging 120

125

it into the settling tank, whereby the sealing medium in the settling tank will be displaced and caused to flow into the collecting means at the base of the holder.

6. In a gas holder the combination of a body or shell; a piston like closure therefor; sealing means involving the use of a liquid sealing medium between the closure and the wall of the body; means located at the base of the holder for collecting the sealing medium; means for withdrawing such water and light oil as may float upon the surface of the sealing medium within the collecting means; a tank having an open but normally inoperative connection with the holder; and means for forcing the withdrawn water and light oil into the tank, whereby the sealing medium will be displaced and caused to flow into the holder.

7. In a gas holder the combination of a body or shell; a piston like closure therefor; sealing means involving the use of a liquid sealing medium between the closure and the wall of the body; means located at the base of the holder for collecting the sealing medium; means for withdrawing such water and light oil as may float upon the surface of the sealing medium within the collecting means; a tank having an open but normally inoperative connection with the holder; means for forcing the withdrawn water and light oil into the tank; and means for removing water and light oil from the tank.

8. In a gas holder the combination of a body or shell; a piston like closure therefor; sealing means involving the use of a liquid sealing medium between the closure and the wall of the body; means located at the base of the holder for collecting the sealing medium; means for withdrawing such water and light oil as may float upon the surface of the sealing medium within the collecting means; a tank having an open but normally inoperative connection with the holder; means for forcing the withdrawn water and light oil into the tank; a float sustained draw-off pipe located within the tank; and a pump connected to said draw-off pipe.

9. In a gas holder the combination of a body or shell; a piston like closure therefor; sealing means involving the use of a liquid sealing medium between the closure and the wall of the body; means located at the base of the holder for collecting the sealing medium; a tank located adjacent the holder, said tank having two pockets, an intake and a discharge pocket, formed therein and in communication with each other at their lower ends, there also being present in the tank a skimmer pocket communicating at its upper edge with the intake pocket; means affording communication between the lower portion of the collecting means and the intake pocket for withdrawal of the sealing medium from the former; means for withdrawing the sealing medium from the discharge pocket and re-

turning the same to the holder; means for withdrawing liquid from the skimmer pocket; and a pressure equalizing connection between the holder and the upper portion of the intake pocket.

10. In a gas holder the combination of a body or shell; a piston like closure therefor; sealing means, involving the use of a liquid sealing medium between the closure and the inner wall of the body; means located at the base of the holder and extending around the same for collecting the sealing medium, water and light oils; a plurality of offtake pipes opening at intervals about the holder into the upper portion of said collecting means; an electrically driven pump connected to each of said pipes; and a timing mechanism for periodically throwing said pumps into and out of action.

11. In a gas holder the combination of a body or shell; a piston like closure therefor; sealing means, involving the use of a liquid sealing medium between the closure and the inner wall of the body; means located at the base of the holder and extending around the same for collecting the sealing medium, water and light oils; a plurality of offtake pipes opening at intervals about the holder into the upper portion of said collecting means; an electrically driven pump connected to each of said pipes; a timing mechanism for periodically throwing said pumps into and out of action; and manually controlled means for placing the pumps in circuit independent of the timing mechanism.

12. In a gas holder the combination of a body or shell; a piston like closure therefor; sealing means, involving the use of a liquid sealing medium between the closure and the inner wall of the body; means located at the base of the holder and extending around the same for collecting the sealing medium, water and light oils; a plurality of offtake pipes opening at intervals about the holder into the upper portion of said collecting means; an electrically driven pump connected to each of said pipes; a timing mechanism for periodically throwing said pumps into and out of action; means causing the sealing liquid to flow outwardly from the collecting means; means for removing water and oil from said liquid; and means for forcing the cleaned sealing liquid back to the upper portion of the holder.

In testimony whereof we have signed our names to this specification.

KONRAD JAGSCHITZ.
PAUL M. KUEHN.

CERTIFICATE OF CORRECTION.

Patent No. 1,829,519.

Granted October 27, 1931, to

KONRAD JAGSCHITZ ET AL.

It is hereby certified that error appears in the printed specification of the above numbered patent requiring correction as follows: Page 5, line 85, claim 4, strike out the article "the" before the word lighter; and that the said Letters Patent should be read with this correction therein that the same may conform to the record of the case in the Patent Office.

Signed and sealed this 8th day of December, A. D. 1931.

(Seal)

**M. J. Moore,
Acting Commissioner of Patents.**
